O. WILLIAMS,
CAP SETTER FOR FUEL ECONOMIZERS.
APPLICATION FILED NOV. 2, 1915.

1,183,263.

Patented May 16, 1916.

UNITED STATES PATENT OFFICE.

OWEN WILLIAMS, OF FALL RIVER, MASSACHUSETTS.

CAP-SETTER FOR FUEL-ECONOMIZERS.

1,183,263.

Specification of Letters Patent. Patented May 16, 1916.

Application filed November 2, 1915. Serial No. 59,305.

To all whom it may concern:

Be it known that I, OWEN WILLIAMS, a citizen of the United States, residing at Fall River, in the county of Bristol and State of Massachusetts, have invented certain new and useful Improvements in Cap-Setters for Fuel-Economizers, of which the following is a specification.

This invention relates to cap setters for fuel economizers.

Those fuel economizers used in connection with steam boiler furnaces which embody a large number of tubes arranged perpendicularly for the utilization of the smoke and products of combustion for the purpose of heating the boiler feed water are closed by a cap or lid maintained in position by pressure from beneath. The flues require cleaning once or twice a year, necessitating the replacement of the caps after cleaning.

At present this is a tedious and time-consuming operation.

My object is to provide a simple, improved and efficient device or appliance for setting these caps by which they may be much more rapidly set than at present is possible so that the time and labor required are very materially reduced. Where as it has heretofore required three men about two days to re-set the caps in an economizer employing about three hundred of these caps, my improved appliance enables re-setting to be accomplished by two men in about one-half a day.

The invention consists of a base of improved form, a novel yoke, a cam lever cooperating therewith, and a bolt of improved construction which can be rapidly and easily applied to the cap and the yoke. Manipulation of the lever causes lifting of the yoke and the elevation of the bolt and cap so that the latter is brought to the top of the tube where it will remain, due to the usual pressure.

In the accompanying drawings:—Figure 1 is a perspective of the appliance; Fig. 2, a side elevation with parts of the yoke and base in section, dotted lines representing the elevation of the parts by the cam lever; Fig. 3, a plan view with the parts in the position shown in Fig. 1, the bolt being omitted; Fig. 4, a detail of the bolt; and Fig. 5, a section on line 5—5, Fig. 4.

The base 1 is provided with an opening 2 of a size adapting it to receive the cap 3 which is to be set, the 5 being provided a

slot 4 leading into the opening 2. Rising from the base are ears or lugs 5 and 6. A yoke 7 has its arms 8 pivoted to the ears 5 at 9 and it is provided with a slot 10 and 60 with grooves 11. The slot 10 is in line with the slot 4 to permit convenient entry or removal of the elevating bolt 12. The bolt 12 is provided with a head 13 whose under edge is rounded or beveled at 14 to seat in the 65 grooves 11 when the bolt is in position. Lower down there is provided a shoulder 15 to prevent the bolt from becoming displaced upwardly beyond a certain limited extent. The lower end of the bolt has a head 16 and 70 is of general rhomboidal form in cross section, as shown at 17. The cap 3 is formed to admit the part 17 when the bolt is advanced transversely in the direction of the length of the slots 4 and 10 and thereafter, 75 upon turning the bolt on its longitudinal axis to an extent substantially equal to ninety degrees, the part 17 engages the cap and the head 16 then has its rounded or 80 beveled part 14 resting in the notches or 85 grooves 11. The parts are then in condition for elevation of the cap. A simple, convenient and easily operable means for elevating the yoke comprises a cam lever 18 pivoted at 19 to the lugs 6 and having its 85 cam 20 disposed under the tip of the yoke 7. In practice, the base 1 will be about six inches long, more or less, and of nearly the same width, and the lever 18 two feet, more or less, in length, so that a very powerful 90 leverage may be obtained with little effort. After one cap has been elevated or set, it will so remain by the pressure and the bolt 12 is then turned to release it from the yoke and it then may be disengaged from the cap 95 and made to engage another cap and again to engage the yoke for the setting of the succeeding cap. The removability of the bolt permits it to be readily engaged with the cap and then with the yoke.

Having thus described my invention, what I claim as new and desire to secure by Letters Patent, is:—

1. In a cap setter, the combination with a base and a movable yoke, the base and yoke 105 having slots or entry openings, of a removable bolt adapted to enter the slots and having means to engage the cap and the yoke, and means for elevating the yoke and with it the bolt.

2. In a cap setter, the combination with a base and a movable yoke, the base and

yoke having slots or entry openings, of a removable bolt adapted to enter the slots and having means to engage the cap and the yoke, and a cam lever adapted to elevate the yoke.

5. 3. In a cap setter, the combination with a base having a laterally extending slot or entry opening, of a yoke having a laterally extending slot or entry opening, the arms of the yoke being pivoted to the base, the aforesaid slots or entry openings being substantially in line, a bolt arranged to be introduced laterally into the slots or entry openings, said bolt having means to engage the yoke and cap when turned, and means for raising and lowering the yoke and with it, the bolt.
10. 4. In a cap setter, the combination with a

base having a laterally extending slot or entry opening, of a yoke having a laterally extending slot or entry opening, the arms of the yoke being pivoted to the base, the aforesaid slots or entry openings being substantially in line, a bolt arranged to be introduced laterally into the slots or entry openings, said bolt having means to engage the yoke and cap when turned, and a cam lever pivoted to the base and arranged to engage with the free portion of the yoke to elevate the latter.
